20-PYRIDYL-5,16-PREGNADIEN-3,20-DIOLS AND LOWER ALKYL DERIVATIVES THEREOF

Raymond M. Dodson, Park Ridge, and Clarence G. Bergstrom, Chicago, Ill., assignors, by mesne assignments, to G. D. Searle & Co., Skokie, Ill., a corporation of Delaware.

No Drawing. Application November 24, 1954, Serial No. 471,119

6 Claims. (Cl. 260—239.5)

The present invention relates to a new group of pyridyl derivatives of pregnadienols and, more particularly, to 20-pyridyl-5,16-pregnadien-3,20-diols and lower alkyl derivatives thereof which can be represented by the general structural formula

wherein R and R' represent hydrogen or lower alkyl radicals, such as methyl, ethyl, propyl, butyl and the like.

These compounds can be synthesized by treatment of 3-hydroxy-5,16-pregnadien-20-one or a readily hydrolyzable ester thereof such as a lower alkanoyl or benzoyl ester with an organometallic pyridine derivative such as pyridyl lithium, pyridyl sodium, methylpyridyl lithium, dimethylpyridyl lithium, ethylpyridyl sodium and the like.

The bases described herein form salts which are non-toxic in therapeutic dosage with a variety of inorganic and strong organic acids such as phosphoric, hydrochloric, hydrobromic, hydriodic, sulfamic, acetic, maleic, malic, succinic, tartaric, citric, ascorbic, gluconic, benzoic, cinnamic, and related acids.

The compounds of this invention are valuable intermediates in the synthesis of medicinally active compounds. They are especially valuable as starting materials for the preparation of solanidinoidal alkaloids. Thus, a compound of the type

is converted by treatment with methanesulfonyl chloride in pyridine to the 20-mesyl ester. The latter is solvolyzed

2

by boiling in dilute ethanol to yield a dehydrosolanidinoid containing an aromatic ring F of the formula

which can then be hydrogenated using sodium or lithium in ethanol or ammonia to form a compound of the type

30 Esterification of the latter with a lower alkanoyl halide or anhydride followed by quaternization with methyl sulfate yields a solanidinium type of quaternary salt of the cationic formula

45 which has a veratrine type of action on the heart muscle. The compounds of this invention can also be oxidized by Openauer oxidation to form the corresponding 4,16-pregnadien-3-ones of the type

60 65 Conventional treatment of the 3,20-diols of this invention with an equivalent of an alkanoyl or aroyl halide

or an alkanoic acid anhydride yields the 3-monoesters.

A special utility of the compounds of this invention is their stimulant action on the hypodynamic or failing heart manifested by a restoration of the deficient contractility of the heart muscle and of the deficient cardiac output. This effect is quite different from the jervine-like depressant cardiac action shown by the corresponding 16,17-dihydro derivatives.

The following examples will illustrate in further detail some of the compounds which constitute this invention and methods for their preparation. However, this invention is not to be construed as limited thereby in spirit or in scope, since modifications in materials and operating conditions can be adopted without departing from the invention. In these examples temperatures are indicated in degrees centigrade and quantities of materials in parts by weight.

Example 1

A solution of butyl lithium in 70 parts of ether is prepared from 1.87 parts of lithium and 16 parts of 1-bromobutane. This solution is cooled to -40°C . and stirred while 17.7 parts of α -bromopyridine are added dropwise in the course of 10 minutes. While stirring is continued a solution of 10 parts of 3β -acetoxy-5,16-pregnadien-20-one in 350 parts of anhydrous ether is added rapidly. The cooling bath is removed and the solution is stirred for 2 hours at room temperature. After standing at room temperature for 15 hours, the solution is treated with 250 parts of water. The ether layer is separated, washed with water to neutrality, dried over anhydrous sodium sulfate, filtered and evaporated to dryness. The residue is applied in benzene solution to a chromatography column containing 900 parts of silica gel. Elution of the column with 7000 parts of a 4% and 7000 parts of an 8% solution of ethyl acetate in benzene removes some impurities. Further elution with 22,500 parts of an 8% solution of ethyl acetate in benzene causes elution of one of the epimeric isomers of 20-(α -pyridyl)-5,16-pregnadien-3 β ,20-diol. A second epimer is eluted with 12,000 parts of a 20% solution of ethyl acetate in benzene. Repeated crystallization from acetone of the first epimer produces a pure product melting at about $186-187^{\circ}\text{C}$. The optical rotation of an 0.705% chloroform solution is $[\alpha]_D = -66^{\circ}$. Ultraviolet maxima are observed at 255.5 and 261 millimicrons with molecular extinction coefficients of 3820 and 4310, respectively. The infrared spectrum shows prominent bands at 2.93, 3.10, 6.30, 7.00, 7.28, 9.38, 10.38, and 13.24 microns.

Repeated crystallization from acetone of the epimer second to be eluted yields a product melting at about $180-182^{\circ}\text{C}$. The specific rotation of a 1.1% chloroform solution is -31.6° . Ultraviolet maxima are observed at 257 and 261 millimicrons with molecular extinction coefficients of 3940 and 4310, respectively. The infrared spectrum shows prominent bands at 2.94, 3.04, 6.29, 6.99, 7.32, 9.43, 9.56, 10.34, and 13.25 microns.

The same reaction can also be carried out with the 3 α -epimer of 3-acetoxy-5,16-pregnadien-20-one. The unacetylated 3-hydroxy-5,16-pregnadien-20-one can likewise be used.

Example 2

A solution of 95 parts of 20-(α -pyridyl)-5,16-pregnadien-3 β ,20-diol, melting at about $186-187^{\circ}\text{C}$., is added to a mixture of 1000 parts of pyridine and 1100 parts of acetic anhydride. After standing at room temperature for 12 hours, the mixture is treated with water to cause precipitation of a 3β -acetoxy-20-(α -pyridyl)-5,16-pregnadien-20-ol which on recrystallization from acetone melts at about $167-168^{\circ}\text{C}$. The rotation of an 0.3% chloroform solution is $[\alpha]_D = -49.5^{\circ}$. The ultraviolet absorption spectrum shows a maximum at 256 millimicrons with a molecular extinction coefficient of 3800,

a maximum at 261 millimicrons with a molecular extinction coefficient of 4300, and a shoulder at about 270 millimicrons with a molecular extinction coefficient of 2150. The infrared spectrum shows maxima at 2.84, 5.76, 6.31, 6.98, 7.24, 7.34, 7.98, 9.64, 12.75, and 13.17 microns, respectively.

Example 3

A solution of 97 parts of the epimer of 20-(α -pyridyl)-5,16-pregnadien-3 β ,20-diol melting at about $180-182^{\circ}\text{C}$. in 1000 parts of pyridine and 1050 parts of acetic anhydride is maintained at room temperature for 12 hours and then treated with water. The resulting precipitate is collected on a filter and crystallized from acetone to yield a 3β -acetoxy-20-(α -pyridyl)-5,16-pregnadien-20-ol melting at about $174-176^{\circ}\text{C}$. The specific rotation of an 0.64% chloroform solution is $[\alpha]_D = -26.6^{\circ}$. The ultraviolet spectrum shows two maxima at 256 and 261.5 millimicrons and a shoulder at 270 millimicrons; the molecular extinction coefficients are 4170, 4600, and 2790, respectively. Infrared maxima are observed at about 2.94, 5.75, 6.29, 6.97, 8.00, and 9.63 microns.

Example 4

Substitution of an equal amount of 3-bromopyridine for the 2-bromopyridine used in Example 1 leads to formation of a mixture of two isomers of 20-(β -pyridyl)-5,16-pregnadien-3,20-diol epimeric at carbon 20. The ultraviolet absorption spectrum shows maxima at 257 and 263 millimicrons with molecular extinction coefficients of about 3900 and 4300, respectively. Infrared maxima are observed at about 2.90, 3.06, 6.30, and 6.98 microns.

Example 5

A solution of butyl lithium in 100 parts of ether, prepared from 3.74 parts of lithium and 32 parts of 1-bromobutane is cooled to -40°C . and then treated by dropwise addition with 35.4 parts of 4-bromopyridine in the course of 10 minutes. Stirring is continued while 20 parts of 3-hydroxy-5,16-pregnadien-20-one in 1000 parts of ether are added. The mixture is then stirred at 25°C . for 6 hours, after which 500 parts of water are added. The ether layer is washed with water to neutrality, filtered and concentrated to dryness. The resulting product is repeatedly recrystallized from acetone to yield 20-(γ -pyridyl)-5,16-pregnadien-3,20-diol. Two isomers epimeric at carbon-20 can be separated by chromatography on silica gel by the method of Example 1. The compound shows an ultraviolet maximum at about 251 millimicrons with a molecular extinction coefficient of about 4300. Infrared maxima are observed at 2.94, 3.08, 6.3, and 7.0 microns.

Example 6

Substitution of 41.6 parts of 2-bromo-4,6-dimethylpyridine for the 4-bromopyridine used in the preceding example, yields 20-(4',6'-dimethyl-2'-pyridyl)-5,16-pregnadien-3,20-diol. The compound shows an ultraviolet plateau at about 260-270 millimicrons with an extinction coefficient of about 4000. It has the structural formula

What is claimed is:

1. A compound of the structural formula

wherein R and R' are members of the class consisting of hydrogen and lower alkyl radicals.

2. 20-pyridyl-5,16-pregnadien-3,20-diol.
3. 20-(α -pyridyl)-5,16-pregnadien-3,20-diol.
4. 20-(β -pyridyl)-5,16-pregnadien-3,20-diol.
5. 20-(γ -pyridyl)-5,16-pregnadien-3,20-diol.
6. 20 - [(lower alkyl)pyridyl]-5,16-pregnadien - 3,20-diol.
